Harry M. Osers, New York, N. Y.

Application April 29, 1953, Serial No. 24,818

Term of patent 7 years

(Cl. D45—19)

To all whom it may concern:

Be it known that I, Harry M. Osers, a citizen of the United States of America, residing at 220 West 42nd Street, New York 18, in the county of New York and State of New York, have invented a new, original, and ornamental Design for a Pin, of which the following is a specification, reference being had to the accompanying drawing, forming part thereof.

In the drawing:

Fig. 1 is a front elevational view of a pin showing my new design;

Fig. 2 is a top plan view thereof; and

Fig. 3 is a sectional view thereof taken along the line 3—3 of Fig. 1.

The dominant features of my design reside in those portions shown in full lines.

I claim:

The ornamental design for a pin, as shown and described.

HARRY M. OSERS.
